UNITED STATES PATENT OFFICE.

GEORGE B. STONE, OF LOS ANGELES, AND FRED D. MICHAELS, OF FRESNO, CALIFORNIA.

LIQUID DRAW OFF.

Application filed May 17, 1927. Serial No. 191,985.

An object of this invention is to provide a simple means in a liquid storage tank for locating the inlet of a discharge, or service pipe, relative to flotation and sedimentation planes, or levels in the tank to the end that only substantially uncontaminated liquid will be delivered to the service pipe.

A further and more specific object is to provide, in a water storage tank, a device which is of simple and inexpensive construction, and facile in installation for the allocation of the inlet end of a draw off pipe with respect to levels, or planes, in the tank subject to contamination by flotation and sedimentation so that only the water between such levels may be delivered.

A still further object is to provide a simple means for controlling the delivery of water from a storage tank which will automatically act to prevent the delivery of contaminating matter of flotation.

A feature of this invention is a device, constructed as a unit, which may be installed with facility without requirement of alteration or change in present storage tanks and their pipings and which operates at all water levels in a tank, to deliver to service faucets, water uncontaminated by matters of sediment or flotation.

Other objects, advantages and features of invention may appear from the accompanying drawing, the subjoined detailed description and the appended claims.

The accompanying drawing illustrates the invention.

Figure 1 shows in sectional elevation a storage tank equipped with a draw off constructed in accordance with our invention.

Fig. 2 is an elevation, on an enlarged scale and partly in section, of the draw-off of our invention.

The tank 1 and supply pipe 2 are, or may be, of any approved conventional construction, and of themselves, except as combined with our improvements, form no part of our invention.

As shown, the service pipe 3 pierces the bottom 4 of the tank and is secured in place as by clamp-nuts 5. Ordinarily the upper, open end of the service pipe serves as outlet for the liquid content and is resident substantially in the plane of the bottom of the tank and in position to draw off the whole content of the tank and deliver for use, undesirable flotation matters, such as oils and greases, which are highly objectionable

for human consumption and sedimentary matters which are objectionable in plumbing and machinery.

As shown, a nipple 6, is secured to the service pipe 3, as by threading to extend the outlet from the tank, that is, the upper end of the service pipe, to a plane, or level, above the bottom of the tank so that delivery of contaminating matter, from the sedimentation level indicated at A is prevented.

A bell 7 is positioned, to completely surround the upper, open end of the nipple 6, which constitutes the outlet of the tank, with its lower, open end occupying a plane below the plane of the upper end of the nipple 6. By preference the bell is provided with a spider 8 for connection with the nipple whereby the handling and installation of the bell and nipple may be facilitated and whereby the bell will be held in proper relation to the nipple.

The bell 7 forms with the nipple 6 an intake passageway or point of communication 9, between the interior of the tank and the open, upper end of the nipple 6, occupying a plane sufficiently below a level, designated as B, in which flotation matter may be held, to prevent delivery of such matter to the outlet.

In order to provide for maximum withdrawal of the tank content without contamination by matter of flotation or sedimentation a guard 10, supported by the nipple and having the form of a saucer is provided, the rim of which extends to a point outwardly, or laterally, from the nipple and in a plane substantially that of the lower end of the bell.

This arrangement of bell and guard in conjunction with the plane of the open, upper end of the service pipe, allows for the bringing of the flotation level B to maximum approximation to the sedimentation level A without danger of delivery of undesirable matter.

To overcome any tendency toward a siphoning action in the bell, creative of suction at the intake passageway 9 and making possible delivery of flotation matter, the bell is vented as by a pipe 11 leading to the top of the tank.

The construction and arrangement of the parts just described provide for the installation of our draw-off without alteration or change of any kind in the tank or its outlet.

The device of this invention is particu-

larly designed for use in connection with storage tanks for water, from which, all, or nearly all, of the water may be drawn and from which undesirable matter of flotation, such as oil and grease, will be not delivered for consumption or use, when the water level reaches the plane of the outlet of the tank. In Fig. 1, the water is shown as drawn off to its lowest limit, as determined by the 10 plane of the outlet, of the upper, open, end of the nipple 6 and as indicated by the letter C. At this water level flotation matter, such as oil and grease, is held in suspension above the line designated B which occupies 15 a plane above the intake passageway 9 and is prevented by the bell 7 from delivery to the faucet 12.

The liquid draw-off of our invention is for use in connection with storage tanks, 20 having variable or inconstant levels of liquid content, and has been particularly devised with regard for facile installation in tanks supplying water for domestic use and to function automatically to deliver, at all 25 times, only relatively pure water, that is, only such water as may be free from undesirable matter such as sand and like sedimentations, or oils and other floatations.

In the extension of the outlet, of the serv- 30 ice pipe, above the sedimentation level as by the nipple 6 and the placing of the bell 7 with its closed top and sides, over the open end of the nipple, there is provided an intake as at 9, which forms the only commu-

nication between the water in the tank and 35 the outlet or nipple 6, and which operates to prevent flotation matter reaching the outlet at all water levels.

We claim:

1. A draw off for liquid storage tanks, 40 constructed as a unit and comprising a nipple, an open bottomed bell covering said nipple, and a guard surrounding the lower end of the bell.

2. A draw off for liquid storage tanks, 45 constructed as a unit and comprising a nipple, an open bottomed bell covering said nipple, a guard surrounding the lower end of the bell, and means for venting the bell to prevent siphoning between the bell and 50 guard.

3. As a new article of manufacture, a liquid draw-off comprising a nipple for extension through the wall of a water storage tank and for connection with a water service pipe; a saucer shaped guard surrounding the nipple adjacent its lower end, and a bell covering the top and sides of the nipple, and having an open bottom extending to substantially the plane of the guard. 60

In testimony whereof, we have hereunto set our hands:

Said STONE at Los Angeles, California, this 5th day of May, 1927.

GEORGE B. STONE.

Said MICHAELS at Fresno, California, this 9th day of May, 1927.
